UNITED STATES PATENT OFFICE.

NELLIE A. EDDINGS, OF GLENDALE, AND HARRY GEARING, OF LOS ANGELES,
CALIFORNIA, ASSIGNORS TO SAID NELLIE A. EDDINGS.

COIN-CONTROLLED VENDING APPARATUS.

1,175,139.

Specification of Letters Patent. Patented Mar. 14, 1916.

Application filed December 9, 1914. Serial No. 876,369.

To all whom it may concern:

Be it known that we, NELLIE A. EDDINGS, a citizen of the United States, and HARRY GEARING, a subject of the King of Great Britain, residing, respectively, at Glendale and Los Angeles, in the county of Los Angeles and State of California, have jointly invented new and useful Improvements in Coin-Controlled Vending Apparatus, of 10 which the following is a specification.

This invention relates to coin controlled vending apparatus, whereby the delivery and purchase of commodities may be effected after the introduction to the apparatus 15 of a coin or object of suitable shape and mass, the apparatus otherwise being inoperative so as to prevent tampering or fraudulent withdrawal or removal of such commodities.

20 The invention relates more particularly to that class of coin controlled apparatus in which the coin, upon its insertion, permits the operation of the apparatus, rather than serving as a working part of the delivery- 25 causing features.

The invention has for its object to provide improved apparatus of the character stated which will be superior in point of relative simplicity and inexpensiveness of construction and organization, taken in connection with positiveness and reliability in action, proof against tampering or unauthorized operation, compactness in form, neatness in appearance, and which will be generally superior in efficiency and serviceability.

With the above and other objects in view, the invention consists in the novel and useful provision, formation, combination, association and inter-relation of parts, members 40 and features, all as hereinafter described, shown in the drawing, and finally pointed out in claims.

In the drawing: Figure 1 is an isometric view, partly broken away for fullness of 45 illustration, of improved coin controlled apparatus constructed in accordance with the invention; Fig. 2 is an enlarged fragmentary vertical sectional view, taken through the coin-receiving operating features of the 50 apparatus, including the coin receptacle, upon the line $\alpha^2-\alpha^2$, Fig. 4 and looking in the direction of the appended arrows; Fig. 3 is an enlarged detail vertical fragmentary sectional view taken upon the line $\alpha^3-\alpha^3$, 55 Fig. 4, and looking in the direction of the

appended arrows, through the commodity storing and delivery features of the apparatus; Fig. 4 is an enlarged fragmentary sectional view taken at right angles to the plane of vision in Figs. 2 and 3, upon the line $\alpha^4-\alpha^4$, Fig. 2, and looking in the direction of the appended arrows; Fig. 5 is a fragmentary sectional view similar to a portion of the showing in Fig. 2, showing the parts in altered position incident to operation; Fig. 6 is a view similar to Fig. 5 showing the parts in further altered position assumed when an unauthorized attempt is made to operate the apparatus, that is without the introduction of the proper coin; 70 and Fig. 7 is a detail fragmentary sectional view, taken on the lines $\alpha^7-\alpha^7$, Fig. 2, and looking in the direction of the appended arrows, features disclosed in Fig. 4 likewise being shown.

75 Corresponding parts in all the figures are designated by the same reference characters.

Referring with particularity to the drawing, the improved coin controlled apparatus 80 disclosed therein as embodying the invention comprises a vertical casing A provided at its top with a cover and lock therefor α and within which the commodities to be vended are stored in vertical columns, separated by vertical transverse parts 8, delivery means B being provided adjacent to the bottom of such casing A, and above a delivery chute b the bottom of which is slightly inwardly and upwardly inclined to promote 85 delivery, and the mouth of which or front opening of which provides egress for the delivered commodities. The casing A is provided with a lateral extension C at its lower portion, within and at which the coin receiving operating means c are disposed, such casing extension having a coin slot 9 whereby suitable coins may be introduced to the member c . The casing extension C is provided between the member c with a coin 90 compartment 10 to which the coins after service in the member c are discharged, such coin compartment having a door and lock therefor, 11, by which such coins may be removed by an authorized person.

100 The delivery means B comprises two commodity trays, 12 and 13, arranged in the same horizontal plane of the casing A, and each mounted upon a bearing 14 at one end rotatably receiving in the side of the cas- 110

ing A away from the casing extension C, the rearward tray 13 having an end bearing 14 at the other end to which is affixed a pinion 15 the teeth of which mesh with a pinion 16 within the casing C, which pinion 16, as will be hereinafter described, is fixed to rotate with the tray 12. The two trays are reversed in position, so that one is inverted while the other is in position to hold the commodity, and being rotatively connected as stated when one is brought into upright position the other is inverted, so that one may discharge commodity to the chute b, while the other receives a charge of commodity.

The means c comprise a shaft 18 projecting through the casing C from the adjacent end of the tray 12, and carrying at its outer end exteriorly of said casing a finger piece 19 whereby such shaft in the tray 12 may be rotated, such shaft being journaled in the casing C, as at 20. The coin receiving operating means c comprise in addition to the shaft 18 the pinion 16 centered upon the shaft 18 and bearing at one face against the adjacent end of the tray 12, the casing A being broken away to permit of such contact, as at 22. Similarly centered upon the shaft 18 is the housing 17, within which are mounted dogs or bolts 23, similar in form, but reversed in positions, top for bottom, and diametrically oppositely arranged with respect to the shaft 18. These bolts 23 are mounted so as to be capable of playing in the housing 17, so that heads 23^a thereof may be projected substantially radially of the housing 17 through slots 23^b therein, such bolts likewise having recesses or seats 23^c adapted to receive coins introduced through the slots 8, when such housing 17 is in the position indicated in Fig. 2. Such bolts 23 are slightly recessed at the top of one and at the bottom of the other, as at 23^d, to accommodate the shaft 18, over which such recessed portions of the bolts slide. The housing 17 is screwed or bolted to the pinion 16, as at 24, and to the adjacent end of the tray 12, so that when the shaft 18 is turned the tray 12 and said disk 50 and housing are turned with the shaft, as the coin in one of the recesses 23^c permits. This can take place, as indicated in Fig. 2, as the coin 25, in one of the seats 23^c, holds the respective dog 23, by engaging with the walls of the respective housing slot 23^c, from engagement with the shouldered end 26^a of a catch slot 26 in the wall of the casing C, within which the housing 17 and pinion 16 are rotatively mounted. This catch slot 26 is formed upon a curved wall having a radius greater than that of the housing 17, whereby the heads 23^a of the bolts 23, by engagement therewith, are held extensionally within the slots 23^b in the housing 17, when forced into engagement with the cen-

tral portion of said curved wall 26^b of such catch slot, by one of two compression springs 27 mounted in the housing 17 and each acting upon one of the dogs or bolts 23 to force it outwardly. If, however, the housing 17 be rotated, without the respective dog 23 being held against outward projection through the slot 23^b by its spring 27, as by a coin introduced within the respective housing slot 23^c and bolt or dog seat 23^a, the respective heads 23^a of the dog or bolt will be projected into the catch slot 26 so as to come into contact with one of the stops 26^a at the ends of such catch slot, thus preventing further rotation of the housing 17 and of the shaft 18 and tray 12 so as to invert the tray and discharge a commodity therefrom. This action is illustrated in Fig. 6. If, as illustrated in Fig. 5, a coin be so inserted, the shaft 18 may be turned to invert the tray 12, the respective dog 23 being retained from projection beyond the housing 17, so that the housing may be rotated through an arc of 180 degrees. When such half rotation has ensued, the coin will pass outwardly through a coin discharge slot 23^c in the wall of the casing C, and downwardly into the coin receiving chamber 10. The other dog 23 will then have been brought into position so that its head 23^a projects within the catch slot 26; and it will be noted that the housing 17 and rotatively coupled parts may be oscillated through an arc determined by the length of the arc of the catch slot 26, for the rotation of such parts to operate the trays 12 and 13 being prevented by the projection of the respective dog 23, unless a coin is introduced within the housing 17 to act in the manner above stated. The dogs 23 of course operate successively in coöperation with the catch slot 26 and its stop walls 26^a. As soon as a coin has been discharged from the housing 17, the member C cannot be further operated until a fresh proper coin is introduced within the respective seat 23^c of the respective dog 23 to coöperate with the housing 17 in the manner stated. Of course the trays 12 and 13 will alternately receive and discharge commodities, the tray which is provided with a commodity being the one to be inverted upon any proper operation of the member c, and the other of such trays being the one to be next positioned to receive a further charge of commodity, having just discharged a previous article or commodity, which is discharged through the chute b. Furthermore, it makes no difference in which direction the shaft 18 is turned, as the trays can be given each a half turn in either case, one to receive commodity and the other to discharge commodity, as permitted by the introduction of coin to control the proper dog 23.

Having thus described our invention we

claim and desire to secure by Letters Patent:

1. In a coin-controlled device, a rotatable housing, a bolt mounted to play in the housing, means with which said bolt is adapted to coöperate to prevent rotation of said housing when projected from the housing, and means tending normally to project the bolt from the housing, said housing and said bolt being provided with coin-receiving openings adapted to register with a coin slot and whereby a coin introduced within the said openings serves to prevent projection of said bolt from said housing by blocking movement of the bolt through engagement by the periphery of the coin of one of the walls of the coin-receiving opening in the bolt and a wall of the coin-receiving opening in the housing to permit rotation of the housing.

2. In a coin-controlled device, a rotatable housing, a pair of bolts mounted to play within the housing, means tending normally to project said bolts from said housing, and means with which said bolts are adapted one at a time to coöperate to prevent rotation of said housing, when projected from the housing; said housing and said bolts being provided with coin-receiving openings whereby a coin introduced in a bolt coin-receiving opening and its respective housing coin-receiving opening may prevent the projection of the respective bolt by blocking the same through engagement by the periphery of the coin of a wall of the coin-receiving opening in the bolt and a wall of the coin-receiving opening in the housing to permit rotation of the housing.

3. In a coin-controlled device, a rotatable housing, a pair of bolts mounted to play within the housing, means tending normally to project said bolts from said housing, and means with which said bolts are adapted one at a time to coöperate to prevent rotation of said housing when projected from the housing; said housing and said bolts being provided with coin-receiving openings whereby a coin introduced between a wall of the coin-receiving opening in one of the bolts and wall of the respective coin-receiving opening in the housing may act through peripheral engagement with said walls to prevent projection of the respective bolt and permit rotation of the housing.

4. In a coin-controlled device, a rotatable housing, a pair of bolts mounted to play within the housing, means tending normally to project said bolts from the housing in

opposite directions, and means with which said bolts are adapted one at a time to coöperate to prevent rotation of said housing, when projected from the housing; said housing and said bolts being provided with coin-receiving openings whereby a coin introduced between the wall of the coin-receiving opening in one of the bolts and a wall of the respective coin-receiving opening in the housing may act through peripheral engagement with said walls to prevent projection of the respective bolt and permit rotation of the housing.

5. In a coin-controlled device, a casing, a rotatable housing, a bolt mounted to play in said housing and project radially through the periphery thereof, means tending normally to project said bolt from said housing, means with which said bolt coöperates to prevent rotation of said housing when projected from said housing, and a formation on said bolt providing a coin-receiving opening; said casing and said housing being provided with coin-receiving openings with which said bolt coin-receiving opening is adapted to register to receive a coin the periphery of which is engaged by said bolt formation and a wall of the coin-receiving opening in the housing thereby preventing projection of said bolt and permitting rotation of said housing.

6. In a coin-controlled device, a rotatable housing, a bolt mounted to play in said housing and project radially through the periphery thereof, means tending normally to project said bolt from said housing, a casing chambered to accommodate rotation of said housing and provided with a plurality of abutting stops to engage said bolt when projected from said housing and prevent rotation of said housing in either direction, and a formation on said bolt adapted to engage the periphery of a coin introduced through suitable slots provided in said casing and said housing; the periphery of the coin so introduced being also engaged by a wall of the coin-receiving slot in the housing and the coin so introduced serving to hold the bolt in retracted position to permit rotation of the housing.

In testimony whereof, we have signed our names to this specification in the presence of two subscribing witnesses.
